(57) **CLAIM**

The ornamental design for a vape cartridge as shown and described.

DESCRIPTION

FIG. 1 is a front perspective view of the new design; FIG. 2 is a front view thereof;

FIG. 3 is a back view thereof;

FIG. 4 is a side view thereof;

FIG. 5 is an opposite side view thereof;

FIG. 6 is a top view thereof; and,

FIG. 7 is a bottom view thereof.

The broken lines in the drawings depict portions of the vape cartridge that form no part of the claimed design. The unshaded area enclosed within the solid lines is not part of the claimed design.
